Thomas Donnelly
ATTORNEY

UNITED STATES PATENT OFFICE.

WILLIAM RYNIEWICZ, OF DETROIT, MICHIGAN.

LOOM OUTLET BOX.

Application filed October 12, 1921. Serial No. 507,167.

To all whom it may concern:

Be it known that I, WILLIAM RYNIEWICZ, a citizen of the United States, residing at Detroit, in the county of Wayne and State 5 of Michigan, have invented certain new and useful Improvements in a Loom Outlet Box, of which the following is a specification.

My invention relates to a new and useful improvement in a loom outlet box or plate 10 and has for its object the provision in a loom outlet box or plate of adjustable means for supporting said plate or box.

Another object is the provision of means for supporting a loom outlet plate or box 15 which will be simple in structure, economical of manufacture and highly efficient in use.

Another object is the provision of supporting means for such a box or plate which 20 will afford means for readily and efficiently securing the plate or box in position and at the same time provide means for securing an insulating plug in position.

Another object is the provision of a loom 25 outlet box or plate together with supporting means therefor which may be easily and quickly arranged for mounting upon differently sized and arranged structures.

Other objects will appear hereinafter. 30 The invention consists in the combination and arrangement of parts hereinafter described and claimed.

The invention will be best understood by a reference to the accompanying drawings 35 which form a part of this specification and in which,

Fig. 1 is a top plan view of the invention,

Fig. 2 is a bottom plan view of the plate used in the invention,

Fig. 3 is a sectional view taken on substantially line 3—3 of Fig. 1,

Fig. 4 is sectional view taken on substantially line 4—4 of Fig. 1.

The invention is designed for use with 45 what is commonly called a loom outlet box or plate, and in this connection it is to be noted that wherever the words box or plate are used in this specification or in the claims they are so used as to be interchangeable. This is so because a plate or box may be used with the invention without any change, the selection as to whether a plate or box is to be used being left to the discretion of the mechanic working on each 55 individual job, and being determined largely by the nature of each particular

piece of work with which it is designed to use the invention.

The invention may be used either with the knob and tube system of outlet boxes or 60 with the conduit system of outlet boxes. The outlet box comprises a box, generally constructed of metal, into which the concealed electric wires are led before passing to the insulating plug to which the fixtures 65 are attached. Inasmuch as this box or plate must support the weight of the fixtures it is necessary that the same be securely fastened in position. This is sometimes very difficult owing to the absence of any secure material 70 to which to fasten it at the point desired. The result is that either the fixture is shifted slightly out of its desired position, insecurely fastened or crude improvised means provided for fastening the box provided. 75 In the last mentioned case the box is often set out considerable distance from the surface to which it is attached with a consequent marring of the appearance of the hanging. The present invention is designed 80 to overcome these difficulties as well as to afford other advantages which will appear as the description proceeds.

The preferred form of construction comprises an outlet box or plate 7. I have 85 shown an outlet plate in the drawings. If it is desired to use a box the walls 8 would be deepened to form the box or a cup-shaped member. Projected through suitable slots formed in the member 7 is a clamping member 9, formed U shaped and terminating at its base in an internally threaded socket 10. Threaded into this socket, before insertion of the member 9 through the member 7, is a stud 11 which is provided at its upper 90 end with a head 12 and at its lower end with a slot or groove 13 which affords a means of turning the stud by means of a screw driver. The ends 14 and 15 of the arms of the U shaped member are doubled 95 upon themselves so as to provide a space into which the legs of a U-shaped supporting bar 16 may be inserted. The member 16 is provided intermediate its ends, at that portion which generally bears the weight 100 of the supported fixture, with a groove or longitudinally extending pocket, the same being formed by pressing the metal of the member 16 inwardly as shown. The bar 16 is provided, adjacent each of its ends 110 with a number of holes 18 through which bolts or screws may be passed for securing

the bar to the joists 19. The plate or box is provided with a number of openings 20 through which the plug or conduit may be passed. These openings are not ordinarily punched out but are merely partly stamped so that the mechanic may punch the metal out of the specific holes or places desired. Pressed in the bar plate 7, at opposite sides of the bar 16 are tits 21 which serve to prevent rotary play of the plate on the bar 16 and the stud 11.

It is evident that the bar 16 provides means for securely fastening the plate regardless of a variation of distances between joists. By having the plate positioned slideably on the bar 16 the position of the fixture may be adjusted as desired. When the proper position of the plate on the bar 16 is determined after the bar is secured in position the plate may be locked in position on the bar by means of the stud 11, said stud being so arranged as to draw the bar 16 and the plate 7 into close engagement, the members which form the engaging jaws thereof being slideable through their length in the plate 7. It is to be noted that the stud 11 projects beyond the end of the socket 10. This projecting portion of the stud is designed to be threaded into the insulating plug which is attached to the pipe which supports the fixture. In this way I have provided a simple method of adjusting the position of the outlet plate and securing the fixture thereto. In case it becomes necessary to dispense with the bar 16 the plate may be secured directly to the supporting surface by means of bolts or screws projected through the openings 22, although such a circumstance would be very rare if it should occur at all.

While I have illustrated and described the preferred form of construction I do not wish to limit myself to the precise form of construction set forth but desire to avail myself of such variations and modifications as come within the scope of the appended claims.

Having thus fully described my invention what I claim as new and desire to secure by Letters Patent is:

1. In combination, a loom outlet plate; a channel-shaped supporting member; means for engaging said supporting member comprising gripping members projected through an opening in said plate and doubled upon

themselves at one side of said plate, and having an interiorly threaded neck at the opposite side of said plate, said neck being of less diameter than the distance between said gripping members, at the point of projection through said plate; and a bolt for threading in said neck, for engaging one side of said plate for clamping said gripping members in engagement with said supporting member, said bolt being provided with an engagement head and being irremovable from said neck while said gripping members are projected through said plate.

2. In combination, a loom outlet plate; a supporting member comprising clamping members projected through an opening formed in said plate and doubled upon themselves; an interiorly threaded neck carried by said gripping members, at the opposite side of said plate, from said doubled over portions, said neck being of less diameter than the distance between said clamping members at the point of projection through said plate, said gripping members tapering inwardly toward each other at one side of said plate, to said neck; and a bolt for threading into said neck for clamping said gripping members in engagement with said supporting member, said bolt being provided with an engagement head and being irremovable from said neck while said gripping members are projected through said plate.

3. In combination, a loom plate; a supporting member therefor; spaced gripping members projected through said plate for engaging said supporting member, said gripping members being inclined toward each other, at the opposite side of said plate, from said supporting member, and formed into an interiorly threaded neck; a bolt for threading into said neck, said bolt being provided with a head adapted for engaging a face of said plate, said bolt being irremovable from said neck, while said gripping members are projected through said plate, said neck and said head being of less diameter than the distance between said gripping members at the point of projection through said plate.

In testimony whereof I have signed the foregoing specification at Detroit, in the county of Wayne and State of Michigan.

WILLIAM RYNIEWICZ.
